Nº 3018

PATENTED
MAY 5 1868

A. A. Smith's Corrugated
Churn Body

L. L. Mc Clintock

W. Monomith

A. A. Smith

United States Patent Office.

A. D. SMITH, OF GRAFTON, OHIO.

Design No. 3,018, dated May 5, 1868.

DESIGN FOR A CHURN-BODY.

The Schedule referred to in these Letters Patent and making part of the same.

TO ALL WHOM IT MAY CONCERN:

Be it known that I, A. D. SMITH, of Grafton, in the county of Lorain, and State of Ohio, have invented or produced a new and original Design in Churn-Bodies; and I do hereby declare the following is a full and exact description of the same, reference being had to the accompanying drawings, making a part of this specification.

Figure 1 is a perspective view.

Figure 2, a sectional.

The nature of my design in churn-bodies, A, consists in the combination of a series of endless ribs, B B B, which run around and form that part of the body A. The ribs being convexed on the outside and concave on the inside, makes more or less the body corrugated.

What I claim, and desire to secure by Letters Patent, is—

The design for a churn-body as herein shown and described.

A. D. SMITH.
